UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING MACHINE

Application filed June 6, 1923. Serial No. 643,617.

My invention relates to mining machines, and more particularly to mining machines of the flexibly fed type.

An object of my invention is to provide an improved mining machine. Another object of my invention is to provide a mining machine of improved and very compact construction especially adapted to use in low vein work. A further object of my invention is to provide an improved feeding mechanism for such a machine. These and other objects and advantages of my improved construction will hereinafter more fully appear.

In the accompanying drawings I have shown for purposes of illustration three forms which my invention may assume in practice.

In these drawings,—

Fig. 1 is a plan view, partially in section, of a mining machine constructed in accordance with one embodiment of my invention, the cutter bar being illustrated in different positions.

Fig. 2 is a side elevation of Fig. 1.

Fig. 3 is an elevation of the feeding end of the machine.

Fig. 4 is a transverse section taken on line 4—4 of Fig. 1.

Fig. 5 is a central longitudinal section taken on line 5—5 of Fig. 1.

Fig. 6 is a plan view, partially in section, of a modified form of construction.

Fig. 7 is a plan view, partially in section, of still another modified form of construction.

Figs. 8, 9, 10 and 11 are diagrammatic views illustrating the manner in which the machine is handled and controlled in operation.

Fig. 12 is a diagrammatic view of the machine making a sumping and running cut showing a modified arrangement of the flexible feeding member.

In this illustrative construction I have shown my invention applied to an air propelled, flexibly fed mining machine of the longwall type adapted to slide on its bottom 1 on a mine bottom and carrying at one end a pivoted cutter bar 2, this construction being such that after the cutter bar has been swung in under the face, the frame portion of the machine, generally designated 3, is disposed

substantially at right angles to the cutter bar and moved longitudinally along the face and relative to a flexible feeding means of any suitable form, herein a cable 4, likewise disposed along the face and operatively connected to the opposite end of the machine from the cutter bar.

Referring more particularly to the machine, it will be noted that the same herein comprises a motor section 5, a feed section 6, and a cutter carrying section 7, the feed and the cutter carrying sections being disposed at opposite ends of the motor section, and rigidly connected to the latter.

The motor section has disposed therein a fluid pressure actuated motor of any approved form, herein comprising a pair of intermeshing toothed rotors 8 and 9 disposed in bores 10 and 11 and being suitably secured, as by keys 12 to shafts 13 and 14 respectively, journaled in heads 15 and 16. Fluid pressure is admitted to the motor through a pipe connection 15' and controlled by a throttle valve 16' from any suitable source of supply. It will be clearly understood that this form of motor is shown for purposes of illustration and that motors other than the air propelled type may be used advantageously.

Operatively associated with the rotors 8 and 9 is the cutting mechanism including the cutter bar 2. More particularly it will be noted that the cutting mechanism includes a cutter bit carrying cutter chain 17 suitably driven from one or the other of the rotors 8, 9, as circumstances require. It will also be noted that a pinion 18, suitably journaled in bearings carried by the motor frame section, is driven from one or the other of the rotors through reversing mechanism arranged in the head 16, herein of a well known form including gears 19 and 20 on the ends of the rotors selectively engageable with a gear 21, whereby the pinion 18 may be rotated in opposite directions as desired under the control of a lever 22 carried on the end of the feed frame section 6. The pinion 18 meshes with a gear 18' suitably secured to a shaft 23 which is suitably journaled in the frame section 7. Driven by the shaft 23 is a worm 24 meshing with a worm gear 24' suitably journaled on a 100

vertical shaft 25 coaxial with the axis of the cutter bar 2. The cutter bar is rigidly connected to a turntable 26 and is provided with projections 27 to which a hook 28, suitably secured to the free end of the cable 4, or a hook 28' secured to the cable 4', is attached when the cutter bar is swung about its axis in its different operative positions, the bar being suitably locked in position by a pin 29 carried by the frame section 7. Operatively connected to the shaft 25 is a cutter chain driving sprocket (not shown) adapted to actuate in a well known manner, the cutter chain 17 which is mounted on the cutter arm. It will be clearly evident that the cutter bit carrying cutter chain 17 may be actuated in opposite directions as conditions require, and that when the gears 19 and 20 are out of engagement with the gear 21 the cutter chain sprocket may remain idle while the motor is running.

Referring more particularly to the feed frame section 6, which incorporates my improved feeding mechanism, it will be noted that suitably secured to the rotor shaft 13 is a pinion 30 rotatable on a longitudinal axis which in turn meshes with a gear 31 suitably journaled on a parallel axis on the feed frame section, this gear having attached thereto a disc 32 having a crank pin 33 to which is connected a connecting rod 34. The connecting rod 34 is herein formed in two parts which are threaded together as at 35 to permit adjustment of the length of the connecting rod, the parts being provided with a lock nut 36 to prevent accidental change of adjustment. At its end remote from the crank pin the connecting rod is also suitably connected through a wrist pin 37 to a rocker arm 38 which is journaled on a sleeve 39 journaled on a longitudinally disposed horizontal shaft 40 suitably secured to the frame section. Keyed to the sleeve is a ratchet wheel 41 adapted to be engaged by a pawl 42 carried by the rocker arm 38 by which the ratchet wheel, and with it the sleeve, may be rotated. It is obvious that the crank pin 33 may be adjusted radially relative to the axis of the crank disk 32 to vary the angular movement of the rocker arm 38 and consequently the speed of rotation of the ratchet wheel 41. Also suitably secured to the sleeve is a pinion 43 which meshes with a gear 44 journaled on a horizontal shaft 45 disposed in the longitudinal center of the machine. This shaft is secured against rotation at its ends in brackets 46 and 47 carried by the feed frame section and has suitably mounted thereon a rotary cable tensioning device, herein in the form of a drum 48 having winding surfaces 49 and 49' of different diameters formed thereon and which may serve as differential drums. A cable 4' which is wound on the surface 49' of the drum is used for sumping the bar

under the coal while the cable 4 wound on the surface 49 of the drum is used for cutting along the face, when a double strand cable is used, and for moving the machine along the face at a faster, or haulage speed, when a single strand cable is used. Interposed between the gear 44 and the drum is a friction clutch 50 comprising a friction surface 51 which is formed on a web integral with the gear 44 and which is adapted to engage a complementary friction surface 51' formed on the drum. The shaft 45 is also threaded, as at 52, to receive a nut 53 provided with a hand-wheel 54, suitable manipulation of the hand-wheel causing the drum to move to the right and pressing the friction surfaces together and thereby rotating the drum with the gear. It is obvious that by varying the amount of pressure between the friction surfaces the speed of rotation of the drum may be accordingly varied. As shown, the flexible feeding member 4 is suitably secured to and wound upon the larger surface 49 of the drum and is adapted to pass around certain of the guide rolls or sheaves 55, 56, 57 and 58 when arranged in different feeding positions. Carried on the rear end of the feed frame are also members 59 with which the hook 28 engages while the machine is cutting.

Referring to Fig. 6 it will be noted that I have shown a modified arrangement which while requiring a longer machine still enables certain of my advantages to be obtained. In this arrangement the rotor shaft 13 is provided with a worm 60 which meshes with a worm gear 61, journaled on a vertical axis, to which a crank disc 62 is secured which in turn drives through a connecting rod 63 and a ratchet wheel and pawl 64 and 65, a vertical shaft 66 to which is secured a worm 67 in turn meshing with a worm gear 68 on a longitudinally disposed horizontal shaft 69 which carries a pinion 70. This pinion in turn meshes with a gear 71 which drives the drum 48. In Fig. 7 I have shown still another modified construction which, while likewise requiring a longer machine than that required by the construction shown in Figs. 1 to 5, enables an even lower machine to be produced. In this construction, the gear 30 meshes with a gear 31 through the connecting rod 34 to the ratchet and pawl 41 and 42 on a sleeve 39. Suitably secured to the sleeve is a worm 72 which meshes with a worm gear 73 journaled on a vertical shaft 74 which in turn drives the cable tensioning device 48 therein rotatable on a vertical axis as distinguished from a longitudinal axis. In this case the cable 4 is also guided by two rolls 75 journaled on vertical shafts on the machine frame.

In the operation of my improved machine it will be noted that the machine is first brought to a position adjacent the face of the coal as shown in Fig. 8 with the cutter bar

swung around in line with the longitudinal axis of the machine. The cable 4' wound on the smaller drum 49' is then passed around the sheave 55 and the hook 28' is attached 5 to the pin 27 adjacent the face. The motor is then started and the friction clutch 50 is thrown in and the cable is wound in, swinging the cutter bar into the face of the coal. Obviously by varying the amount of application 10 of the friction clutch, the rate of swing of the bar may be varied through a considerable range. When the cutter bar is at substantially right angles to the machine frame 3 the motor is stopped and the bar is locked in 15 position by the pin 29. The cable 4 is then passed around the sheave 56 forwardly along the face and around a pulley secured to an anchor jack A and then rearwardly along the face and attached to the member 59 by means 20 of the hook 28 as shown in Fig. 9. The motor is then started again and the machine advances along the face of the coal at a slow or cutting speed, the rate of feed at any time being capable of being varied by the friction 25 clutch or by adjusting the crank pin 33 away from or toward the center of the crank disk 32. It is obvious that any other suitable means for varying the throw of the pawl may be used advantageously. When the machine 30 cuts at the opposite face as shown in Fig. 11 or in the opposite direction, the cutter bits are turned in the chain 17, the sumping cut being made by attaching the cable 4' at the opposite side of the bar, as shown by Fig. 10, and 35 the machine cuts transversely along the face. Fig. 12 shows a slightly different arrangement utilizing a single drum, the cable 4 then being passed along the face to the jack A and then rearwardly along the face and attached to the cutter bar. With this arrangement the bar may obviously be swung in under the coal and locked in position, and the machine then moved transversely along the face without rearranging the cable or stopping 40 the motor, or in any way using the drum 49', which in this construction may be omitted if desired.

As a result of my improved construction it will be noted that a machine of improved compact construction is obtained, the length of 50 the machine being materially reduced by disposing the drum on a longitudinal axis as distinguished from a vertical axis with or without the drum driving connections having 55 the ratchet wheel rotatable on a longitudinal axis, while the improved arrangement of the ratchet mechanism with or without the drum on a longitudinally disposed axis likewise produces a similar result, thereby materially 60 facilitating handling at the same time that the weight and cost of the machine is substantially reduced. It will also be noted that an exceedingly low machine of the drum type is produced, the disposition of the drum on 65 a longitudinal axis enabling a large drum to

be used without increasing the height, while the use of a horizontal drum with my improved ratchet mechanism enables an even lower machine to be produced while keeping down the length of the machine otherwise necessary where such a drum is used. These and other advantages of my improved construction will be clearly apparent to those skilled in the art. 70

While I have in this application specifically described three forms which my invention may assume in practice, it will be understood that these forms of the same are shown for purposes of illustration and that the invention may be modified and embodied in various other forms without departing from its spirit or the scope of the appended claims. 75

What I claim as new and desire to secure by Letters Patent is:

1. In a mining machine, a horizontal motor having its axis extending longitudinally of the machine, reversible cutting mechanism driven by said motor, and feeding mechanism adapted to feed said machine in opposite directions during either direction of cutting including a cable winding drum rotatable continuously in only one direction during feeding of the machine while cutting in opposite directions and whose axis is disposed parallel to a line parallel with the axis of said motor, cooperating guiding means, driving mechanism between said motor and said drum, and a feed cable cooperating with said drum having a free end portion and guiding means for said free end portion for feeding the machine during either direction of cutting. 85

2. In a mining machine, a horizontal motor having its axis extending longitudinally of the machine, and feeding mechanism including winding means disposed at one end of said machine and having flexible feed member winding surfaces of different diameters and arranged coaxially with said motor axis, and driving mechanism between the adjacent end of said motor and said winding means. 95

3. In a mining machine, a motor, reversible cutting mechanism driven thereby, and feeding mechanism driven thereby including a unidirectionally rotational winding drum disposed on an axis extending longitudinally of the machine and cooperating guiding means, and a flexible cable associated with said drum and said guiding means and operative to feed said machine in either direction during either direction of cutting and during continuous unidirectional rotation of said drum and without disconnecting the driving connection between said drum and motor. 115

4. In a mining machine, a uni-directionally rotational motor, reversible cutting mechanism driven thereby, and feeding mechanism driven thereby including a uni-directional rotational winding drum disposed on 120

an axis extending longitudinally of the machine and cooperating guiding means, and a flexible cable associated with said drum and said guiding means and operative to feed said machine in either direction during either direction of cutting and during uni-directional rotation of said drum.

5. In a mining machine, a non-reversible motor, reversing gearing, reversible cutting mechanism driven thereby, and feeding mechanism driven by said motor including a flexible feed member, and an actuating member therefor cooperating directly therewith and rotatable on a horizontal axis in a single direction and cooperating guiding means for said flexible member, said mechanism being adapted to feed said machine in either direction during cutting in opposite directions and while maintaining said flexible member in a single operative relation to said actuating member.

6. In a mining machine, a non-reversible motor, reversible cutting mechanism adapted to be driven in opposite directions thereby, and feeding mechanism including a flexible feed member, an actuating member engaging directly said flexible feed member and rotatable on an axis extending longitudinally of the machine, cooperating guiding means for said feed member, said feed member being adapted to have a single operative connection with respect to said actuating member, said mechanism being adapted to feed said machine in either direction during cutting in opposite directions.

7. In a mining machine, a horizontal motor having its axis disposed longitudinally of the machine, cutting mechanism driven from one end of said motor, feeding mechanism including a winding member disposed at one end of said machine and having winding surfaces of different diameters and whose axes are disposed longitudinally of said motor, and cooperating flexible feeding means including separate flexible elements cooperating with said winding surfaces respectively, and means to drive said winding member from the opposite end of said motor.

8. In a mining machine, a horizontal motor having its axis disposed longitudinally of the machine, cutting mechanism driven from one end of said motor, feeding mechanism including a winding drum disposed on a horizontal axis extending longitudinally of the machine at the end of the latter remote from said cutting mechanism and having stepped winding surfaces thereon, and cooperating flexible feeding means including separate feed cables cooperating with said winding surfaces respectively, and means to drive said drum from the opposite end of said motor.

9. In a mining machine, a motor having its axis extending longitudinally of the machine, cutting mechanism driven from the rear end 65 of said motor, and feeding mechanism driven

from the front end of said motor including a winding drum disposed on an axis extending longitudinally of said motor, and driving mechanism between said motor and drum to drive the latter including mechanical means to vary the speed of said driving mechanism and mechanical means to vary the speed of said drum independently of said driving mechanism.

10. In a mining machine, a motor having its axis extending longitudinally of the machine, cutter chain operating mechanism driven thereby, feeding mechanism driven from the front end of said motor and including a winding drum rotatable on an axis disposed longitudinally of the machine, and actuating means for said mechanisms driven by said motor including a plurality of independently adjustable controlling means for varying the speed of said drum, said drum being driven only through both of said speed varying means.

11. In a mining machine, a frame, a feed operating member thereon rotatable on an axis extending longitudinally of said machine frame and having stepped operating surfaces adapted to engage separate elements of a flexible feeding means, driving mechanism therefor including variable speed transmission mechanism, and an independent controlling mechanism for said feed operating member including a friction clutch through which said feed operating member is driven.

12. In a mining machine, a frame having a feeding mechanism adapted to feed the machine in opposite directions including a feed operating member thereon rotatable in a vertical plane on an axis extending longitudinally of the machine and having a plurality of operating surfaces adapted to engage separate flexible feeding means, and cooperating guiding members for said flexible feeding means disposed on each side of the axis of said feed operating member, said feed operating member rotating continuously in only one direction and without disconnecting the same from said motor and said flexible feeding means maintaining a single operative relation to said feed operating member during feeding of the machine in opposite directions.

13. In a mining machine, a horizontal motor having its axis extending longitudinally of the machine, and feeding mechanism driven by said motor including a feed operating member disposed on an axis extending longitudinally of the machine and parallel to a line parallel with the axis of said motor, and driving mechanism for said feed operating member including a variable speed ratchet mechanism including an oscillatory element movable in a vertical plane extending transversely of the machine, and a cooperating ratchet disposed on an axis parallel with the axis of said feed operating member.

14. In a mining machine, a motor, cutting

mechanism driven from one end of said motor, and feeding means driven from the other end of said motor including a feed operating member disposed on an axis extending longitudinally of the machine, and driving mechanism between said motor and feed operating member including a variable speed ratchet mechanism including an oscillatory element movable in a vertical plane extending transversely of the machine and a ratchet disposed on an axis parallel with the axis of said member.

15. In a mining machine, a machine frame slidable directly on its bottom on the mine bottom during cutting, a motor carried thereby by having its axis extending longitudinally of the machine, cutting mechanism driven from one end of said motor including a cutter bar pivoted on a vertical axis, and feeding means driven from the other end of said motor for feeding the machine bodily laterally over the mine bottom, including a winding drum whose axis lies in a line perpendicular to said vertical axis, and ratchet mechanism disposed between said motor and drum including an oscillatory element movable in a vertical plane extending transversely of the machine.

16. A mining machine comprising a frame, cutting mechanism including a cutter bar at one end thereof, feeding mechanism including a plurality of winding drums at the opposite end thereof, and cooperating flexible feeding means including separate cables cooperating with said drums respectively, a motor between said mechanisms and operatively connected to said cutting mechanism, and operative connections between said motor and said drums including an oscillatory element movable in a vertical plane extending transversely of the machine and a ratchet whose axis extends longitudinally of the machine.

17. A mining machine comprising a frame, cutting mechanism including a cutter bar at one end thereof, feeding mechanism including a winding drum disposed at the opposite end thereof and whose axis extends longitudinally thereof, a motor between said mechanisms and operatively connected to said cutting mechanism, and operative connections between said motor and said drum including a ratchet mechanism and actuating means therefor whose axes are horizontal, said ratchet mechanism including an oscillatory element movable in a vertical plane extending transversely of the machine.

18. A mining machine comprising a frame, cutting mechanism including a cutter bar at one end thereof, feeding mechanism including a plurality of winding drums disposed at the opposite end thereof and whose axes extend longitudinally of the machine, and cooperating flexible feeding means having separate feed cables cooperating with said drums respectively, a motor between said mechanisms and operatively connected to said cutting mecha-

nism, and operative connections between said motor and said drums including a ratchet mechanism and actuating means therefor whose axes are disposed horizontally, said ratchet mechanism including an oscillatory element movable in a vertical plane extending transversely of the machine.

19. A longwall mining machine comprising a frame, cutting mechanism including a cutter bar at one end thereof, feeding mechanism including a plurality of winding drums at the opposite end thereof, and cooperating flexible feeding means including separate cables cooperating with said drums respectively, a motor between said mechanisms and operatively connected to said cutting mechanism, and operative connections lying generally in a single horizontal plane between said motor and said drums including a ratchet mechanism disposed in a vertical plane extending transversely of the machine and including a ratchet member rotatable on an axis extending longitudinally of the machine.

20. A longwall mining machine comprising a frame, cutting mechanism including a cutter bar at one end thereof, feeding mechanism including a winding drum disposed at the opposite end thereof and whose axis extends longitudinally of the machine, a motor between said mechanisms and operatively connected to said cutting mechanism, and operative connections between said motor and said drum including a ratchet mechanism disposed in a plane extending transversely of the machine and including a ratchet, the axes of said drum and ratchet lying generally in the same horizontal plane.

21. A mining machine comprising a frame, a motor thereon comprising a plurality of intermeshing rotors, cutting mechanism selectively connectible to either rotor to effect drive thereof in opposite directions, mechanism driven by said motor for feeding the machine during either direction of cutting including a winding drum of a diameter substantially equal to the height of the machine and rotatable on an axis extending longitudinally of the machine, and operative driving connections between said drum and one of said rotors.

22. A mining machine comprising a frame, a motor thereon comprising a plurality of intermeshing rotors having their axes horizontally disposed and extending longitudinally of the machine, cutting mechanism selectively connectible to either rotor to effect drive thereof in opposite directions, mechanism driven by said motor for feeding the machine during either direction of cutting including a winding drum of a diameter substantially equal to the height of the machine and rotatable in a vertical plane on a horizontal axis extending longitudinally of the machine, and

operative driving connections between said winding drum and one of said rotors.

23. A mining machine comprising a frame, a horizontal motor thereon comprising a plurality of intermeshing rotors, cutting mechanism selectively connectible to either rotor to effect drive thereof in opposite directions and including a horizontally swingable cutter bar, and mechanism driven by said motor for feeding the machine during either direction of cutting including a winding drum of a diameter substantially equal to the height of the machine and rotatable in a vertical plane on a horizontal axis extending longitudinally of the machine, and variable speed driving connections between said winding drum and said motor.

24. A longwall mining machine comprising cutting mechanism including a pivoted cutter bar at one end thereof, feeding mechanism at the other end thereof including a plurality of feed operating members of different diameter each disposed on an axis extending longitudinally of said machine and cooperating flexible feeding means including separate flexible members cooperating with said feed operating members respectively, and a horizontal motor having its axis extending longitudinally of the machine and disposed between said mechanisms and operatively connected thereto at opposite ends thereof.

25. A longwall mining machine comprising cutting mechanism including a pivoted cutter bar at one end thereof, feeding mechanism at the other end thereof including a plurality of coaxially disposed feed operating members of different diameter disposed on an axis extending longitudinally of said machine and cooperating flexible feeding means including separate flexible members cooperating with said feed operating members respectively, and a horizontal motor having its axis extending longitudinally of the machine and disposed between said mechanisms and having its opposite ends respectively operatively connected thereto.

26. A longwall mining machine comprising cutting mechanism including a pivoted cutter bar at one end thereof, feeding mechanism at the other end thereof including a plurality of feed operating members of different diameter each disposed on an axis extending longitudinally of said machine, a horizontal motor having its axis extending longitudinally of the machine and disposed between said mechanisms and having its opposite ends respectively operatively connected thereto, and flexible feeding means including separate feeding elements adapted to cooperate directly with different feed operating members.

27. A longwall mining machine comprising cutting mechanism including a pivoted cutter bar at one end thereof, feeding mecha-

nism at the other end thereof including a plurality of coaxially disposed feed operating members of different diameter each disposed on an axis extending longitudinally of said machine, a horizontal motor having its axis extending longitudinally of the machine and disposed between said mechanisms and having its opposite ends respectively operatively connected thereto, and flexible feeding means including separate feeding elements adapted to cooperate directly with different feed operating members.

28. A longwall mining machine comprising cutting mechanism including a pivoted cutter bar at one end thereof, feeding mechanism including a plurality of feed operating members of different diameter each disposed on an axis extending longitudinally of said machine, a horizontal motor having its axis extending longitudinally of the machine and disposed between said mechanisms and having its opposite ends respectively operatively connected thereto, flexible feeding means adapted to cooperate directly with different feed operating members, and means whereby one of said feed operating members may be utilized to swing the bar and the other to move the machine bodily along a face.

29. A longwall mining machine comprising cutting mechanism including a pivoted cutter bar at one end thereof, feeding mechanism including a plurality of coaxially disposed feed operating members of different diameter disposed on an axis extending longitudinally of said machine, a horizontal motor having its axis extending longitudinally of the machine and disposed between said mechanisms and having its opposite ends respectively operatively connected thereto, flexible feeding means adapted to cooperate directly with different feed operating members, and means whereby one of said feed operating members may be utilized to swing the bar and the other to move the machine bodily along a face.

30. A longwall mining machine comprising cutting mechanism including a pivoted cutter bar at one end thereof, feeding mechanism including a plurality of feed operating members of different diameter each disposed on an axis extending longitudinally of said machine, a horizontal motor between said mechanisms and operatively connected thereto, a plurality of flexible feeding members adapted to cooperate directly with different feed operating members, and means whereby the flexible member on the feed operating member of smaller diameter may be used as a single strand connection to swing the bar and the other flexible member used as a double strand connection to move the machine bodily along the face.

31. A longwall mining machine comprising cutting mechanism including a pivoted cutter bar at one end thereof, feeding mecha-

- nism including a plurality of coaxially disposed feed operating members of different diameter disposed on an axis extending longitudinally of said machine, a horizontal 5 motor between said mechanisms and operatively connected thereto, a plurality of flexible feeding members adapted to cooperate directly with different feed operating members, and means whereby the flexible member 10 on the feed operating member of smaller diameter may be used as a single strand connection to swing the bar and the other used as a double strand connection to move the machine bodily along the face.
- 15 32. A longwall mining machine comprising cutting mechanism including a pivoted cutter bar at one end thereof, feeding mechanism including a plurality of coaxially disposed feed operating members of different 20 diameter each disposed on an axis extending longitudinally of said machine, a motor between said mechanisms and operatively connected to said cutting mechanism, and operative connections between said motor and said 25 feed operating members including ratchet mechanism having a ratchet wheel rotatable on a longitudinal axis and disposed between said motor and said feed operating members, and a friction clutch disposed between said 30 feed operating members and said ratchet mechanism.
33. In a mining machine, feeding mechanism therefor comprising a feed operating member rotatable on an axis extending longitudinally of the machine, a flexible feeding member cooperating directly therewith and having a free end portion, and guide means for said flexible member disposed at each side of said feed operating member on inclined axes whereby said free end portion of said flexible feed member may be guided from opposite sides of the machine for feeding the machine in opposite directions without rereeing said flexible member relative to said feed operating member.
34. In a mining machine, flexible feeding means including a flexible feed member having a free end portion, a flexible feed member engaging and actuating means rotatable on an axis extending longitudinally of the machine, and flexible feed member guide means disposed at each side of said machine on inclined axes and adapted to guide a flexible feed member substantially tangentially of said actuating means whereby the free end portion of said flexible member may be guided from opposite sides of the machine during feeding of the machine in opposite directions without rereeing said flexible member relative to said feed member actuating means.
35. In a mining machine, flexible feeding means including a flexible feed member having a free end portion, a flexible feed member engaging and actuating means rotatable 55 on an axis extending longitudinally of the machine, and flexible feed member guide means disposed on each side thereof and rotatable on relatively angularly disposed axes whereby the free end portion of said flexible member may be guided from opposite sides of the machine during feeding of the machine in opposite directions without rereeing the flexible member relative to said feed member actuating means.
36. In a mining machine, feeding mechanism therefor comprising a flexible feed member having a free end portion, flexible feed member engaging and actuating means rotatable on an axis extending longitudinally of the machine, and flexible feed member guide means disposed on each side thereof and rotatable on relatively angularly disposed axes, the guide means on one side thereof being substantially tangential to the upper side of said actuating means while the other guide means is substantially tangential to the lower side thereof whereby the free end portion of said flexible feed member may be guided from opposite sides of the machine during feeding of the machine in opposite directions without rereeing said flexible member relative to said feed member actuating means.
37. In a mining machine, feeding mechanism therefor comprising separate flexible feed members each having a free end portion, flexible feed member engaging and actuating means having different diameters with which said feed members respectively cooperate and disposed on an axis extending longitudinally of the machine, and flexible feed member guide means adapted to guide said flexible feed members substantially tangentially of said different diameters whereby the free end portion of each of said flexible means may be extended from opposite sides of the machine during feeding of the machine in opposite directions without rereeing the flexible means relative to said feed member actuating means.
38. In a mining machine, feeding mechanism therefor comprising flexible feeding means including separate flexible feed members each having a free end portion, flexible feed member engaging and actuating means having different diameters with which said feed members respectively cooperate and disposed on an axis extending longitudinally of the machine, and flexible feed member guiding means disposed on each side thereof, said latter means each including a plurality of guide members certain of which are adapted to guide a flexible member substantially tangentially of one side of each of the different diameters while the means on the other side is adapted to guide a flexible member substantially tangentially of the other side of the diameters whereby the free end portions of said flexible members may be guided from 120 125 130

opposite sides of the machine during feeding of the machine in opposite directions and without rereeing said flexible members relative to said feed member actuating means.

39. In a mining machine, a frame, a cutter bar projecting from one end thereof, a motor, flexible feed member actuating means rotatable about a horizontal axis extending longitudinally of the machine and disposed generally at the other end of said frame, and ratchet mechanism for actuating said means disposed in a vertical plane extending transversely of the machine and bodily between said motor and means.

40. In a mining machine, a frame, a cutter bar projecting from one end thereof, a motor, flexible feed member actuating means rotatable about an axis extending longitudinally of the machine and disposed generally at the other end of said frame, and ratchet mechanism for actuating said means disposed bodily between said motor and means and including an oscillatory element movable in a vertical plane extending transversely of the machine.

41. In a mining machine, a frame, a cutter bar projecting from one end thereof, a motor also carried thereby, flexible feed member actuating means carried generally at the other end of said frame and rotatable about an axis extending longitudinally of the machine, and ratchet mechanism for actuating said means disposed generally in a vertical plane extending transversely of the machine and bodily between said motor and means.

42. In a mining machine, a motor, cutting mechanism driven from one end of said motor including a cutter bar projecting from one end of said machine, and feeding means driven from the other end of said motor including flexible feed member actuating means carried at the other end of said machine, said means comprising a plurality of drums each rotatable on an axis extending longitudinally of the machine frame, and one of which is adapted to be used during a sumping operation and the other during a lateral feeding operation.

43. In a mining machine, a motor, reversible cutting mechanism driven from one end of said motor including a projecting cutter bar, and feeding means driven from the other end of said motor including a plurality of flexible feed member engaging and actuating members each rotatable on an axis extending longitudinally of the machine, and means for guiding different flexible members to said actuating members from opposite sides of said machine to effect feed of the machine during opposite directions of cutting.

44. A mining machine slideable over a mine bottom on its bottom including a frame having at one end thereof a pivoted cutter bar having reversible cutting mechanism associated therewith and operative on actuation

of said cutting mechanism associated therewith oppositely to cut and clear kerfs in opposite directions when the machine frame is oppositely propelled, and means for feeding said machine in opposite directions during cutting in either direction including unidirectionally rotational cable winding drums adjacent the other end of said frame and rotatable upon a horizontal axis extending longitudinally of said frame, cables cooperating with said drums respectively and having free end portions, and guiding means for the free end portions of said cables including guide members arranged in pairs at opposite sides of the central longitudinal vertical plane of said machine frame and at the end of the latter remote from said cutting mechanism.

45. In a mining machine, feeding mechanism therefor comprising a feed operating member rotatable on an axis extending longitudinally of the machine, a flexible feeding member cooperating directly therewith and having a free end portion, and guide means for said flexible member disposed at each side of said feed operating member whereby said free end portion of said flexible member may be guided from opposite sides of the machine for feeding the machine in opposite directions without rereeing the same relative to said feed operating member.

46. In a mining machine, a horizontal motor having its axis extending longitudinally of the machine, and feeding mechanism driven by said motor including a feed operating member, and driving mechanism between said motor and said feed operating member including a variable speed ratchet mechanism including an oscillating element movable in a vertical plane extending transversely of the machine and disposed bodily between said motor and said feed operating member, and a manually controllable friction clutch between said ratchet mechanism and said feed operating member.

47. A mining machine comprising a frame, a motor thereon comprising a plurality of intermeshing rotors, cutting mechanism selectively connectible to either rotor to effect drive thereof in opposite directions during cutting in opposite directions, mechanism driven by said motor for feeding the machine during either direction of cutting including a winding drum of a diameter substantially equal to the height of the machine and rotatable on an axis extending longitudinally of the machine, and a cable cooperating with said drum, said cable having but a single operative relation to said drum during feeding of the machine in either direction, and operative driving connections between said drum and one of said rotors.

48. A mining machine comprising a frame, a motor thereon comprising a plurality of intermeshing rotors having their axes horizontally disposed and extending longitudi-

- 10 nally of the machine, cutting mechanism selectively connectible to either rotor to effect drive thereof in opposite directions during cutting in opposite directions, mechanism driven by said motor for feeding the machine during either direction of cutting including a winding drum of a diameter substantially equal to the height of the machine and rotatable in a vertical plane on a horizontal axis extending longitudinally of the machine, and a cable cooperating with said drum, said cable having but a single operative relation to said drum during feeding of the machine in either direction, and operative driving connections between said winding drum and one of said rotors.
- 15 49. A mining machine comprising a frame, a horizontal motor thereon comprising a plurality of intermeshing rotors, cutting mechanism selectively connectible to either rotor to effect drive thereof in opposite directions during cutting in opposite directions and including a horizontally swingable cutter bar, and mechanism driven by said motor for feeding the machine during either direction of cutting including a winding drum of a diameter substantially equal to the height of the machine and rotatable in a vertical plane on a horizontal axis extending longitudinally of the machine, and a cable having but a single operative relation to said drum during feeding of the machine in either direction, and variable speed driving connections between said winding drum and said motor.
- 20 50. In a mining machine, a machine frame slidable directly on its bottom on the mine bottom during cutting, a horizontal motor carried thereby having its axis extending longitudinally of the machine, cutting mechanism driven from one end of said motor including a horizontally swingable cutter bar, and feeding mechanism driven from the opposite end of said motor for feeding the machine bodily laterally over the mine bottom
- 25 including a feed operating member and driving mechanism between said motor and said feed operating member including a variable speed ratchet mechanism including an oscillating element movable in a vertical plane extending transversely of the machine and disposed bodily between said motor and said feed operating member.
- 30 51. In a mining machine, a horizontal motor having its axis disposed longitudinally of the machine, reversible cutting mechanism driven by said motor adapted to cut in opposite directions, and feeding mechanism including a winding member disposed at one end of said machine and having winding surfaces of different diameters and whose axes are disposed longitudinally of said motor, flexible feeding members cooperating with said winding surfaces of said winding members, said winding members rotating in only one direction and said flexible members hav-
- 35 ing only a single operative relation to said winding member during feeding of the machine in opposite directions, and means to drive said winding member from said motor.
- 40 52. In a mining machine, a horizontal motor having its axis disposed longitudinally of the machine, reversible cutting mechanism adapted to cut in opposite directions driven by said motor, and feeding mechanism including a drum disposed on a horizontal axis extending longitudinally of the machine and having stepped winding surfaces thereon, flexible members cooperating with said winding surfaces of said drum, said drum rotating in only one direction and said flexible members having but a single operative relation to said drum during feeding of the machine in opposite directions, and means to drive the drum from said motor.
- 45 53. In a mining machine, a motor, cutting mechanism driven from one end of said motor including a cutter bar projecting from one end of said machine, and feeding means driven from the other end of said motor including flexible feed member actuating means carried at the other end of said machine, said means comprising a plurality of drums one of which is rotatable on an axis extending longitudinally of the machine frame.
- 50 54. In a mining machine, a motor, cutting mechanism driven from one end of said motor including a cutter bar projecting from one end of said machine, and feeding means driven from the other end of said motor including flexible feed member actuating means carried at the other end of said machine, said means comprising a plurality of drums one of which is rotatable on an axis extending longitudinally of the machine frame, and one of which is adapted to be used during a sumping operation and the other during a lateral feeding operation.
- 55 55. In a mining machine, a motor, reversible cutting mechanism driven from one end of said motor including a projecting cutter bar, and feeding means driven from the other end of said motor including a plurality of flexible feed members engaging and actuating members one of which is rotatable on an axis extending longitudinally of the machine, and means for guiding different flexible members to said actuating members from opposite sides of said machine to effect feed of the machine during opposite directions of cutting.
- 60 56. A mining machine slidable over a mine bottom on its bottom including a frame having at one end thereof a pivoted cutter bar having reversible cutting mechanism associated therewith and operative on actuation of said cutting mechanism associated therewith oppositely to cut and clear kerfs in opposite directions when the machine frame is oppositely propelled, and means for feeding said machine in opposite directions during cutting

in either direction including a uni-directionally rotational cable winding drum rotatable continuously in the same direction irrespective of the direction in which said cutting mechanism is actuated and disposed adjacent to the other end of said frame and rotatable upon a horizontal axis extending longitudinally of said frame, a cable cooperating with said drum, said cable having but a single operative relation to said drum during feeding of the machine in either direction, and guiding members adapted to cooperate with said cable and selectively operative dependent upon the direction of feed and arranged at opposite sides of the end of said frame remote from said cutting mechanism.

57. A mining machine slidable over a mine bottom on its bottom including a frame having at one end thereof a pivoted cutter bar having reversible cutting mechanism associated therewith and operative on actuation of said cutting mechanism associated therewith oppositely to cut and clear kerfs in opposite directions when the machine frame is oppositely propelled, and means for feeding said machine in opposite directions during cutting in either direction including uni-directionally rotational cable winding drums adjacent the other end of said frame and rotatable upon a horizontal axis extending longitudinally of said frame, cables cooperating with said drums and having free end portions, and having but a single operative relation to said drums during feeding of the machine in either direction, and guiding means for the free end portions of said cables including guide members arranged in pairs at opposite sides of the central longitudinal vertical plane of said machine frame and at the end of the latter remote from said cutting mechanism.

58. A longwall mining machine comprising cutting mechanism including a pivoted cutter bar at one end thereof, feeding mechanism at the other end thereof including a plurality of feed operating members each adapted to cooperate directly with flexible feeding means and disposed on an axis extending longitudinally of the machine, and a horizontal motor having its axis extending longitudinally of the machine and disposed between said mechanisms and operatively connected thereto at opposite ends thereof.

59. A longwall mining machine comprising cutting mechanism including a pivoted cutter bar at one end thereof, feeding mechanism at the other end thereof including a plurality of coaxially disposed feed operating members disposed on an axis extending longitudinally of the machine and each adapted to cooperate directly with flexible feeding means, and a horizontal motor having its axis extending longitudinally of the machine and disposed between said mechanisms and having its op-

posite ends respectively operatively connected thereto.

60. A longwall mining machine comprising cutting mechanism including a pivoted cutter bar at one end thereof, feeding mechanism at the other end thereof including a plurality of feed operating members each adapted to cooperate directly with flexible feeding means and disposed on an axis extending longitudinally of the machine, a horizontal motor having its axis extending longitudinally of the machine and disposed between said mechanisms and having its opposite ends respectively operatively connected thereto, and flexible feeding means adapted to cooperate with different feed operating members.

61. A longwall mining machine comprising cutting mechanism including a pivoted cutter bar at one end thereof, feeding mechanism at the other end thereof including a plurality of coaxially disposed feed operating members disposed on an axis extending longitudinally of the machine and each adapted to cooperate directly with flexible feeding means, a horizontal motor having its axis extending longitudinally of the machine and disposed between said mechanisms and having its opposite ends respectively operatively connected thereto, and flexible feeding means adapted to cooperate with different feed operating members.

62. A longwall mining machine comprising cutting mechanism including a pivoted cutter bar at one end thereof, feeding mechanism including a plurality of feed operating members each disposed on an axis extending longitudinally of said machine and adapted to cooperate directly with flexible feeding means, a horizontal motor having its axis extending longitudinally of the machine and disposed between said mechanisms and having its opposite ends respectively operatively connected thereto, flexible feeding means adapted to cooperate with different feed operating members, and means whereby one of said feed operating members may be utilized to swing said bar and the other to move the machine bodily along a face.

63. A mining machine comprising a low compact frame slidable on its bottom on the mine bottom and including a motor casing directly engaging the mine bottom and housing a horizontal motor having its axis extending longitudinally of the machine, the height of said motor being only that requisite for the power producing function thereof and its height determining the height of the machine, cutting mechanism driven from one end of said motor including a cutter bar projecting from said frame at one end thereof, and feeding means driven from the opposite end of said motor including a plurality of feed operating members rotatable on horizontal axes, and flexible feeding means in-

cluding separate feeding elements cooperating directly with different feed operating members.

64. A mining machine comprising a low compact frame slidable on its bottom directly on the mine bottom and including a motor casing directly slidably engaging the mine bottom and housing a horizontal motor having its axis extending longitudinally of the machine, the height of said motor being only that requisite for its power producing function and determining the height of the machine, cutting mechanism driven from one end of said motor including a pivoted cutter bar at one end of said frame, and feeding means driven from the opposite end of said motor including a plurality of feed operating members rotatable on horizontal axes and disposed at the end of said frame remote from said bar pivot, and flexible feeding means including separate feeding elements cooperating directly with different feed operating members.

65. A mining machine comprising a low compact frame slidable on its bottom directly on the mine bottom and including a motor casing directly slidably engaging the mine bottom and housing a horizontal motor having its axis extending longitudinally of the machine, the height of said motor being only that requisite for its power producing function and determining the height of the machine, cutting mechanism driven from one end of said motor including a pivoted cutter bar at one end of said frame, and feeding means driven from the opposite end of said motor including a plurality of feed operating members rotatable on horizontal axes and disposed within the lateral limits of said frame at the end of said frame remote from said bar pivot, and flexible feeding means including separate feeding elements cooperating directly with different feed operating members.

66. A mining machine comprising a frame slidable on its bottom on the mine bottom and including a motor casing housing a horizontal motor having its axis extending longitudinally of the machine, cutting mechanism driven from one end of said motor including a cutter bar projecting from said frame at one end thereof, and feeding means driven from the opposite end of said motor including coaxial feed operating members rotatable on a horizontal axis, and flexible feeding means including separate feeding elements cooperating directly with different feed operating members.

67. A mining machine comprising a frame slidable on its bottom on the mine bottom and including a motor casing housing a horizontal motor having its axis extending longitudinally of the machine, cutting mechanism driven from one end of said motor including a cutter bar projecting from said frame at

one end thereof, and feeding means driven from the opposite end of said motor including coaxial feed operating members rotatable on a horizontal axis extending longitudinally of the machine, and flexible feeding means including separate feeding elements cooperating directly with different feed operating members.

68. A mining machine comprising a frame, a motor thereon comprising a plurality of intermeshing rotors, cutting mechanism selectively connectible to either rotor to effect drive thereof in opposite directions during cutting in opposite directions, mechanism driven by said motor for feeding the machine during either direction of cutting including a plurality of winding drums rotatable on axes extending longitudinally of the machine, cables cooperating with said drums respectively, said cables having but a single operative relation to said drums during feeding of the machine in either direction, and operative driving connections between said drums and one of said rotors.

69. A mining machine comprising a frame, a motor thereon comprising a plurality of intermeshing rotors having their axes horizontally disposed and extending longitudinally of the machine, cutting mechanism selectively connectible to either rotor to effect drive thereof in opposite directions during cutting in opposite directions, mechanism driven by said motor for feeding the machine during either direction of cutting including a plurality of winding drums rotatable in vertical planes on horizontal axes extending longitudinally of the machine, and cables cooperating with said drums respectively, said cables having but a single operative relation to said drums during feeding of the machine in either direction, and operative driving connections between said winding drums and one of said rotors.

70. A mining machine comprising a frame, a horizontal motor thereon comprising a plurality of intermeshing rotors, cutting mechanism selectively connectible to either rotor to effect drive thereof in opposite directions during cutting in opposite directions and including a horizontally swingable cutter bar, and mechanism driven by said motor for feeding the machine during either direction of cutting including a plurality of winding drums rotatable in vertical planes on horizontal axes extending longitudinally of the machine and cables having but a single operative relation to said drums during feeding of the machine in either direction, and variable speed driving connections between said winding drums and said motor.

71. A longwall mining machine comprising cutting mechanism including a pivoted cutter bar at one end thereof, feeding mechanism including a plurality of feed operating members each disposed on an axis ex-

tending longitudinally of the machine and disposed at the end of the machine remote from said bar pivot, a horizontal motor having its axis extending longitudinally of the machine and disposed between said mechanisms and having its opposite ends respectively operatively connected thereto, and flexible feeding means adapted to cooperate directly with different feed operating members.

10 In testimony whereof I affix my signature.
CHARLES F. OSGOOD.
